 a corporation of Indiana

No Drawing. Application August 18, 1950,
 Serial No. 180,296

21 Claims. (Cl. 260—644)

2

1 The present invention relates to the nitration of aliphatic hydrocarbons. More particularly, it pertains to the production of nitro hydrocarbons by the vapor phase nitration of aliphatic hydrocarbons at elevated temperatures by means of nitric acid, oxides of nitrogen, and the like, in the presence of regulated amounts of a halogen or a halogen-containing compound, as more particularly described hereinafter.

Numerous efforts have been made in the past to develop a satisfactory method of producing nitro hydrocarbons. The most effective previously disclosed processes are those of Hass et al. described in U. S. Patent Nos. 1,967,667, 2,071,122, and 2,206,813, pertaining to the vapor phase nitration of paraffin hydrocarbons such as ethane, propane, butane and the like, by means of nitric acid or nitrogen dioxide, and that of Landon, described in U. S. Patent No. 2,161,475, pertaining to the nitration of methane by means of nitric acid.

All of the prior art processes are open to a number of serious objections, the most important of which have been the low yields based on hydrocarbons used and low conversions based on the nitric acid used in the process. Because of the cost, corrosiveness, and the like of nitric acid, it is highly desirable to use as small a quantity as possible. We have now discovered that the conversion of nitric acid and yields of nitro hydrocarbons, as well as the production of valuable oxidation products when hydrocarbons are nitrated in the vapor phase, can be materially increased by effecting the vapor phase nitration of the hydrocarbons in the presence of a halogen or a halogen-containing compound in regulated amounts under certain restricted conditions of time, temperature, etc.

Another aspect of our invention involves the use of regulated amounts of molecular oxygen in addition to the halogen or halogen-containing compound. The use of oxygen in the manufacture of nitroalkanes by the vapor phase nitration of paraffin hydrocarbons is known, being described and claimed in copending application, U. S. Serial No. 15,504, filed March 17, 1948, now abandoned, by Hass and Alexander. It has not been previously known, however, that greatly improved yields and conversions of nitro hydrocarbons can be obtained by the use of a halogen, either in the presence or absence of molecular oxygen. During the course of the investigation which led to the present invention we discovered that improved yields and conversions of nitro hydrocarbons are obtained when a free

halogen is present during the nitration reaction, whether or not molecular oxygen is also present.

The improved process whereby we obtain increased yields and conversions of both nitro hydrocarbons and oxidation products such as alcohols, aldehydes, acids, etc., consists essentially of conducting the vapor phase nitration of aliphatic hydrocarbons at temperatures ranging from 200 to 500° C. with a nitrating agent such as nitric acid in contact with a free halogen, or halogen-containing material, and in the presence or absence of molecular oxygen. For each mole of nitric acid used, we have found that from about 7 to about 35 moles of hydrocarbons, from about .0018 to .026 mole of free halogen and not more than about 3.0 moles of molecular oxygen should be used. By carrying out the nitration under such conditions, the conversions to nitro hydrocarbons are increased by as much as 50% over those obtained by the method of nitration in the presence of oxygen, and by more than 150% over those obtained by the conventional methods of nitration in the absence of oxygen. Such increases permit the production of nitro hydrocarbons at materially lower cost because of increases in plant capacity, lower raw material cost, and lower labor cost. Even relatively low increases in conversions are of great importance in the production of relatively expensive materials such as the nitro hydrocarbons.

Our process is, in general, applicable to the nitration of aliphatic hydrocarbons which are gaseous under the conditions of the process, i. e. at temperatures between 200 and 500° C. Our process is especially advantageous for the nitration of paraffins, such as ethane, propane, n-butane, iso-butane, the pentanes, the hexanes, the heptanes, and the octanes; but it is also applicable with advantage to other aliphatic hydrocarbons, saturated and unsaturated, such for instance as the cycloparaffins, and olefins and acetylenes having 3 or more carbon atoms in the molecule.

Our process may be satisfactorily carried out over a wide temperature range, i. e. 200 to 500° C., depending upon the hydrocarbon being nitrated, the products desired and other conditions. However, the reaction time must be altered in accordance with the temperature used; substantially longer times being required for the lower temperatures, and substantially shorter times being required for the higher temperatures for optimum conversion of nitric acid to nitro hydrocarbons. The particular hydrocarbon be-

ing nitrated also has some effect on temperature and contact time. For paraffins, nitration temperatures decrease somewhat for a given contact time as chain length and branching increases. Lower temperatures are usually required for nitration of olefins and acetylenes. In general, the contact times used when a halogen, or halogen-containing material is present do not differ substantially from those used in nitrations carried out according to the conventional methods, with or without molecular oxygen present. Accordingly, in carrying out our improved process the temperatures, reaction times, and space velocities are regulated in the same general manner as in the prior art processes.

In general, we have found that the optimum contact times vary inversely with the temperatures employed. As the temperature is raised from 200 toward 500° C., the optimum time of contact decreases from about 15 seconds to slightly less than 1 second. The optimum time of contact for a given reaction temperature can most conveniently be determined for a given reaction mixture by regulating the time of contact for the reaction mixture at the selected reaction temperature so as to maintain the acidity of the reaction products within a relatively narrow range. Since water is one of the reaction products of the nitration reaction, and the nitro hydrocarbons are in all cases at least partially immiscible with water, the liquid reaction products separate into two layers. The titratable acidity of the aqueous layer constitutes a convenient measure of the acidity of the reaction products, and this value may be used as a basis for the control of the time-temperature factor. If the acidity of the aqueous layer of the reaction products rises above the desired operating range, the reaction temperature should be increased, or the contact time increased (space velocity decreased), or both of these changes may be made simultaneously. Similarly, if the acidity of the aqueous layer drops below the desired operating range, the reaction temperature should be decreased, or the contact time should be decreased (space velocity increased), or both of these changes may be made simultaneously. Since it is usually desirable to operate at constant space velocity, it is most convenient merely to adjust the reaction temperature in accordance with the acidity of the aqueous layer. Very small adjustments in temperature will cause relatively large fluctuations of the acidity, and the temperature adjustments should therefore be made gradually. The acidity of the aqueous layer of the product (expressed in normality), should be maintained within the range of 0.1 N. to 1.5 N in order to obtain best results. The optimum value within this range, in any given case, will depend upon the particular hydrocarbon being nitrated, and on the composition of the reaction mixture. This general procedure is more completely disclosed in U. S. Patent No. 2,327,964 by Edward B. Hodge, granted August 24, 1943.

While the exact amount of halogen to be added varies somewhat with the temperature, the hydrocarbon to nitric acid ratio, the amount of oxygen, if any, the contact time, and the type of reactor employed, it can be said in general that greatly improved yields and conversions are obtained when catalytic proportions of from about .0018 to .026 mole of a halogen is added per mole of nitric acid. Larger quantities than .026 mole can be added with increased conver-

sions resulting, but the amount of the increase may not be great enough to warrant the use of more halogen. Smaller quantities than .0018 mole of halogen can also be used but diminishing effects on the yield of nitro paraffins may be encountered.

We have found that any halogen can be used in our process although the use of fluorine is not practical due to its highly corrosive nature. Excellent results are obtainable when chlorine, bromine or iodine is employed as the catalyst. The catalytic action of the halogens is produced only by the free elements, and it is therefore desirable to add the halogens as such; that is, uncombined with other elements. Thus chlorine, iodine and bromine can advantageously be added as their gases and iodine as solid element. Inasmuch as most halogen-containing compounds are readily oxidized by nitric acid under the conditions of the nitration reaction, we have found that we are not limited to the use of the free elements, but can use any compound which is oxidized by nitric acid to give a free halogen, and which does not form other substances which are harmful to the nitration reaction. Particularly suitable for this purpose are the hydrogen halides, HBr, HCl and HI, the alkyl halides, and acyl halides. Also suitable are the compounds composed of two halogens, IBr and ICl. The amounts of halogens given above, for example .0018 to .026 mole per mole of nitric acid, refer to the free elements so that the optimum mole ratios for halogen-containing compounds must be calculated from the number of halogen atoms contained in each molecule of the particular compound.

The method of employing halogens in our improved process may be varied somewhat without departing from the concepts of our invention.

For example, the halogen or halogen containing compound can be added to the hydrocarbon before or after the introduction of the nitric acid. We have generally thought it advantageous, however, to vaporize the nitric acid into the hydrocarbon and then to add the halogen to this mixture before heating to reaction temperature. On other occasions we have found it advantageous to preheat the halogen-hydrocarbon mixture for several seconds at a temperature of from 300 to 500° C. before adding nitric acid. Excellent results are also obtained when the halogen or halogen-containing compound is added to the nitric acid prior to entry into the reaction zone.

The concentration of the nitric acid used may be varied over a wide range without materially affecting the results, 19% nitric acid giving results equally as good as 70% nitric acid. We have found that excellent results are obtained with nitric acid having a concentration within the range 19 to 85%.

Quite unexpectedly we have found that molecular oxygen, when used together with halogens, gives increased yields and conversions when used in amounts only up to 3.0 moles per mole of nitric acid. When larger quantities of oxygen are added, the catalytic action of the halogens is completely defeated and yields and conversions drop sharply. This limit on the amount of oxygen which can be used is entirely unexpected and is directly contrary to the situation with oxygen when no halogen is present. For example, U. S. Serial No. 15,505, now Patent No. 2,573,662, discloses that no upper limit to the increase of conversion has been found as the proportion of oxygen is raised toward the explosive limit.

The molecular oxygen used in our process may be added either as substantially pure oxygen or as a mixture with other gases. Another surprising aspect of the present invention, however, lies in the discovery of the fact that when air is used as the oxygen source the catalytic effect of the halogens is sharply reduced. This is not to be construed as meaning that air cannot be used as the oxygen source since some catalytic action is effected even in the presence of air; that is, the yields and conversions are substantially greater than when no halogen is present. This discovery, that air is not as effective as substantially pure oxygen, is in direct conflict with the teaching of U. S. Serial No. 15,504, wherein it is disclosed that equally good results are obtained with air as with substantially pure oxygen.

The process of incorporating oxygen in the reaction mixture can be varied in accordance with different procedures outlined above for incorporating halogens. The particular method used for adding the oxygen is not a critical feature of our invention, and any of the methods known to the art can be used advantageously.

Although our process has been described generally with reference to nitric acid as the nitrating agent, nitrogen dioxide can also be used and halogens exert the same beneficial effect when employed with this nitrating agent. Slightly different conditions are required, however, for using nitrogen dioxide in our process.

As previously indicated, our process gives rise not only to increased conversions and yields of nitro hydrocarbons but also to the increased formation of oxidation products from the hydrocarbon being used. Increased amounts of these oxidation products represent one of the valuable advantages of our process in view of the fact that it gives rise to the formation of sufficient products of this character to justify their recovery from the water-soluble fraction of the nitration reaction. It is especially noteworthy that by far the largest increases in yields of oxidation products is that for aldehydes. Therefore, it can be said that the gain in yields of nitro hydrocarbons has been made at the expense of substantially worthless by-products.

A better understanding of the nature and concepts of our invention can be had by reference to the following examples, which are presented for purpose of illustration only and are in no way intended to limit the invention:

EXAMPLE I

A reaction mixture consisting of 20.4 moles of propane and 1 mole of 19% nitric acid was passed in the vapor phase through a reactor consisting of a 40-foot coil of "Pyrex" glass tubing (7 mm. diameter) immersed in a fused salt bath at a temperature of 423° C., the contact time being about 1.8 seconds.

In a similar run there was passed through the identical apparatus a reaction mixture consisting of 22.8 moles of propane and 1 mole of 19% nitric acid and 0.015 mole of bromine at a temperature of 423° C. and a contact time of 1.9 seconds.

The results of these two runs, given in Table I below, show that, without any oxygen being added, the addition of 0.015 mole of bromine to a nitration reaction gives an increase in yield based on nitric acid and conversion based on propane.

EXAMPLE II

To determine the effect of varying amounts of oxygen on the catalytic action of bromine in the nitration of propane, additional runs were made in the same reactor described in Example I. In these runs the amount of bromine added was maintained constant. The results, shown in Table II, indicate that the addition of oxygen is beneficial only so long as the mole ratio of oxygen to nitric acid is maintained below about 3.0. The optimum mole ratio of oxygen to nitric acid is proven to be about 1.0 for a bromine to nitric acid mole ratio of 0.015.

EXAMPLE III

Another series of runs was made in the reactor described in Example I, but with a different bromine to nitric acid ratio, and at varying temperatures. The results in Table III, serve to illustrate how each of the many variables affect the yields and conversions when using bromine. This example shows that for the particular conditions employed, a temperature of 418° C. is the optimum for nitration.

8 EXAMPLE VI

A reaction mixture consisting of 12.9 moles of propane and 1 mole of nitric acid was passed through a reactor as described in Example I. In this run iodine was introduced into the reactor as a catalyst. The iodine was introduced as a mixture with the propane, the propane being passed through a tared containing crystalline iodine. The amount of iodine vaporized was controlled by varying the amount of iodine in the bulb and the iodine-propane contact surface. The results and conditions of this run are given in Table VI.

It is to be understood, of course, that we are not limited to the specific operation procedure set forth in the above specific examples since various modifications of the procedure set forth therein will naturally occur to those skilled in the art. For example, the process may be operated in a cyclic manner if desired. Various methods of bringing the reacting gases to the desired reaction temperature may be employed. More concentrated solutions of nitric acid than those shown in the specific examples may also be used. Still other variations common to the prior art may be employed and it is distinctly under-

stood that we may so vary our claimed invention so long as the particular improvement hereinbefore disclosed and covered by the appended claims is followed.

We claim:

1. In a process for the production of improved yields of nitro hydrocarbons by the vapor phase nitration of aliphatic hydrocarbons, the improvement which comprises contacting about 1 mole of nitric acid with about 7 to 35 moles of an aliphatic hydrocarbon and from .0018 to .026 mole of a halogen selected from a group consisting of chlorine, bromine and iodine, said mixture being maintained at a temperature between about 200 and 500° C. for a sufficient period of time to permit substantial nitration of the hydrocarbons.

2. In a process for the production of improved yields of nitro hydrocarbons by the vapor phase nitration of aliphatic hydrocarbons, the improvement which comprises contacting about 1 mole of nitric acid with about 7 to 35 moles of an aliphatic hydrocarbon, not more than 3.0 moles of oxygen and from .0018 to .026 mole of a halogen selected from the group consisting of chlorine, bromine and iodine, said mixture being maintained at a temperature between about 200 and 500° C., for a sufficient period of time to permit substantial nitration of the hydrocarbons.

3. The process of claim 2 wherein the reaction time is from 1 to 15 seconds.

4. The process of claim 2 wherein the reaction time is regulated such that the acidity of the aqueous reaction products is maintained at a substantially constant value which is between 0.1 N and 1.5 N.

5. The process of claim 2 wherein the hydrocarbon is a saturated aliphatic hydrocarbon.

6. The process of claim 2 wherein the hydrocarbon is a saturated aliphatic hydrocarbon having a boiling point below about 200° C.

7. The process of claim 2 wherein the hydrocarbon is an acetylene having 3 or more carbon atoms.

8. The process of claim 2 wherein the hydrocarbon is an olefin having 3 or more carbon atoms.

9. In a process for the production of improved yields of nitro hydrocarbons by the vapor phase nitration of aliphatic hydrocarbons, the improvement which comprises contacting in the gaseous phase, about 1 mole of nitric acid with about 7 to 35 moles of an aliphatic hydrocarbon, less than about 3.0 moles of oxygen and from .0018 to .026 mole of a halogen selected from the group consisting of chlorine, bromine and iodine, said gaseous mixture being maintained at a temperature between about 200 and 500° C., for about 1 to 15 seconds, and separating the nitro hydrocarbons from the reaction mixture.

10. The process of claim 9 wherein the hydrocarbon is a saturated aliphatic hydrocarbon.

11. The process of claim 9 wherein the hydrocarbon is propane.
12. The process of claim 9 wherein the hydrocarbon is butane.
13. The process of claim 9 wherein the hydrocarbon is ethane.
14. The process of claim 9 wherein the halogen is chlorine.
15. The process of claim 9 wherein the halogen is bromine.
16. The process of claim 9 wherein the nitric acid has a concentration of between about 19 and 85%.
17. The process of claim 9 wherein the halogen is introduced as a halogen-containing compound.
18. The process of claim 9 wherein the halogen is introduced as a compound selected from the group consisting of halogen hydrides, alkyl halides and acyl halides.
19. In the vapor phase nitration of hydrocarbons with a nitrating agent selected from the group consisting of nitric acid and nitrogen dioxide, the improvement which comprises conducting the nitration reaction with the reactants in contact with catalytic proportions of a compound selected from the group consisting of the free halogens, chlorine, bromine and iodine, and oxidizable compounds of these halogens.
20. In the vapor phase nitration of hydrocarbons with a nitrating agent selected from the group consisting of nitric acid and nitrogen dioxide, the improvement which comprises conducting the nitration reaction with the reactants in the presence of oxygen in contact with catalytic proportions of a compound selected from the group consisting of the free halogens, chlorine, bromine and iodine, and oxidizable compounds of these halogens.
21. In the vapor phase nitration of hydrocarbons the improvement which comprises mixing at elevated temperatures a nitrating agent selected from the group consisting of nitric acid and nitrogen dioxide, with an aliphatic hydrocarbon and catalytic proportions of a compound selected from the group consisting of the free halogens, chlorine, bromine and iodine, and oxidizable compounds of these halogens, and maintaining said mixture at elevated temperatures for a sufficient period of time to permit substantial nitration of the hydrocarbons.
